UNITED STATES PATENT OFFICE.

FRED BERGWALL, OF CHICAGO, ILLINOIS, ASSIGNOR TO BERNARD D. WEYAND, OF CHICAGO, ILLINOIS.

CAR-DOOR-LOCKING DEVICE.

Application filed January 29, 1917, Serial No. 145,049. Renewed March 3, 1922. Serial No. 540,917.

To all whom it may concern:

Be it known that I, FRED BERGWALL, a citizen of the United States, residing at Chicago, in the county of Cook and State of Illinois, have invented a certain new and useful Improvement in Car-Door-Locking Devices, of which the following is a specification.

This invention relates to car-door locking devices and has for its object to provide a new and improved device of this description. One of the difficult problems in connection with transporting materials by railway cars is to prevent the car doors from being surreptitiously opened, and the object of the present invention is to provide a car door locking device which will hold the door in its closed position and prevent access to the car by springing the edge of the door and which will also indicate any tampering with the lock. The invention is particularly adapted to be used in connection with frangible seals. The invention is illustrated in the accompanying drawing, wherein—

Fig. 1 is a view with parts broken away showing a car door with the locking device applied.

Fig. 2 is a sectional view taken on line 2—2 of Fig. 1.

Fig. 3 is an enlarged sectional view taken on line 3—3 of Fig. 2.

Fig. 4 is an enlarged sectional view taken on line 4—4 of Fig. 2.

Fig. 5 is a view similar to Fig. 2 with the locking part moved longitudinally to its unlocking position.

Like numerals refer to like parts throughout the several figures. Referring now to the drawings, I have shown a car door 1 adapted to be slid laterally to open and shut the door. The car door may be suspended in any desired manner as by means of the rail 2 fastened to the car 2^a, and the sliding engaging devices 3 fastened to the door. The locking device in this case is particularly adapted to be placed at the rear edge of the door. The locking device is provided with a base 4 which is fastened to the car door. This base is provided with an opening through which projects the locking part 5 of the locking device, there being a handle 6 connected with this locking part by means of which it can be rotated. The end of the locking part is provided with a projection 7. Attached to the car body is a metal plate

8, having an opening 9 for the locking part 5. The plate 8 is arranged with a beveled face 10 and the projection 7 is provided with a beveled face 11. It will thus be seen that when the locking part 5 is moved inwardly through the plate 8 and is then rotated, the beveled faces on the plate 8 and the projection 7 are brought into engagement and the door 1 is clamped against the side of the car. The front of the door, when closed, abuts against a stop 1^c. The opening 9 in the plate 8 is not a circular opening but has one dimension greater than the other, so that the projection 7, when the locking part is turned in one position, may easily pass through said opening, but when turned in another position, engages the plate 8, as shown in Fig. 3. I also prefer to have this opening sufficiently large to permit the locking part to pass therethrough even though the car door has sagged down. The locking part 5 is arranged so that it may be moved longitudinally as well as rotated, so that after the projection 7 has been disengaged from the plate 8 by rotating the locking part, it may then be moved longitudinally through the opening 9 in the plate 8 so as to become entirely disengaged from the car body. I also prefer to arrange the construction so that when the locking part 5 is moved longitudinally to its unlocked position it can not be rotated, so that the part 7 will always be in proper position to enter the opening 9. I further prefer to arrange the parts so that after the locking part is moved to its locking position and rotated to cause the projection 7 to engage plate 8, it can not then be moved longitudinally but can be rotated. I secure this result by providing a stop 12 which engages a shoulder 13 when the locking part is in its locked position, so as to prevent longitudinal movement thereof. When the locking part is in its unlocked position, rotation thereof is prevented due to the fact that a flat face 14 engages the stop 12, said flat face sliding under the stop 12 when the locking part is moved to its unlocked position. In the construction shown, the stop 12 consists of a pin extending between the branches of a U-shaped piece 15 at the back of the base 4 and preferably integral therewith. I prefer to arrange the lock so that a frangible seal may be used therewith. As herein shown, the locking part 5 is provided at the

front of the base 4 with a projection 16 which projects out over the base. This projection is recessed at 17 to provide a portion of the receiving space for the frangible seal 17^a shown in dotted lines and is also provided with a seal breaking part 18, which engages the overhanging parts 19 and 20, which prevent lateral movement thereof. After the seal is placed in position, it is held from removal by the rotating part 20, which has an over-lapping end 21 which overlaps the seal. This rotating part 20 may be rotated in one direction, but can not be rotated in a reverse direction, and it is provided with an engaging face 22 which engages the frangible seal when the part 20 is in its operative position, and prevents any further rotation in the forward direction without breaking the seal. The rotation in the reverse direction is prevented by means of a pawl 23 which engages teeth 24 on the stem of the part 20. The pawl is elastically held against the tooth portion by means of a spring 25. The stem of the part 20 passes through the base 4 and the tooth portion and pawl are concealed back of the base 4 so as not to be accessible. The base 4 is fastened to the car door so that it can not be removed from the outside, as for example, by bolts 1^a which pass through the door and which are provided with nuts 1^b on the inside of the door, so that when the door is closed, the base 4 can not be removed. Some means is preferably provided for stopping the handle 6 when the locking part has been moved to its unlocked position and before it is moved laterally to bring the flat face of the locking part under the pin 12. In the construction shown, this result is produced by means of a suitable stop, as for example, by the face of the part 16 striking a stop face 26. This is shown by the dotted lines in Fig. 1. Means are also arranged for stopping the handle when the locking part has been rotated to its locking position. This may be accomplished by means of a projection 27 which engages a stop 28 (see Fig. 1). I may arrange the device so that a wire, tin or other looped seal may be used. This may be accomplished by providing slots 27^a and 27^b in the parts 27 and 28, so that when they are in the position shown in full lines in Fig. 1 this seal may be looped through them. I have described in detail a particular construction embodying the invention but it is, of course, evident that the parts may be varied in many particulars without departing from the invention, and I do not, therefore, limit myself to the particular construction shown.

The use and operation of my invention are as follows:

When it is desired to lock the door, the door is slid to its closed position and by means of the handle 6 the locking part 5

is moved longitudinally until the projection 7 passes through the opening 9. The handle is then rotated until the projection 7 engages the plate 8 as shown in Fig. 2. The stops then prevent further rotation of the handle which is in the position shown in full lines in Fig. 2. The rear of the door is now locked and tightly pressed and clamped against the car body and is held both against sliding and against being pried out or moved away from the car body, thus completely preventing access to the car. The front of the door abuts against the part 1^c and hence can not be tampered with. The frangible seal is now placed in position and the rotating part 20 rotated until the projecting part 21 projects over the seal. The handle 6 can not now be moved without breaking the seal. When it is desired to enter the car, the handle 6 is rotated and the seal-breaking part 18 engages the edge of the frangible seal and breaks it, thus permitting the locking part to be rotated. The locking part 5 is then moved longitudinally as shown in Fig. 3 the projection 7 being thus moved through the opening 9 disconnecting the lock from the car body. The door can then be slid to one side. It will thus be seen that by means of this construction the door is held so as to completely exclude unauthorized persons from the car and that any unauthorized person can only get into the car by breaking the frangible seal and thus disclosing that the car has been tampered with.

I claim:

1. A car door locking device comprising a base adapted to be fastened to the car door, a locking part rotatably and slidably mounted in said base, said locking part provided with a locking projection, an engaging device connected with the body of the car adapted to be engaged by the locking projection by giving the locking part a sliding and rotating movement, and a frangible seal having a connection with said locking part so that the locking part cannot be moved without disturbing said seal and means for attaching a flexible seal to said locking part.

2. A car door locking device comprising a base, a locking part slidably and rotatably mounted in said base so that it may be rotated and also moved longitudinally, a locking projection projecting laterally from said locking part, an engaging device connected with the body of the car adapted to be engaged by the locking projection by giving the locking part a longitudinal and rotating movement and means for holding said locking part against rotation when in its unlocking position.

3. A car door locking device comprising a base, a locking part slidably and rotatably mounted in said base so that it may be ro-

tated and also moved longitudinally, a locking projection projecting laterally from said locking part, an engaging device connected with the body of the car adapted to be engaged by the locking projection by giving the locking part a longitudinal and rotating movement, said engaging part and projecting locking part having co-acting beveled faces and means for holding said locking part against rotation when in its unlocking position.

4. A car door locking device comprising a base, a locking part slidably and rotatably mounted in said base so that it may be rotated and also moved longitudinally, a locking projection projecting laterally from said locking part, an engaging device connected with the body of the car adapted to be engaged by the locking projection by giving the locking part a longitudinal and rotating movement, a stop for preventing the locking part from being moved longitudinally when the locking projection is in its locking position and two different styles of sealing means for said locking part so that it cannot be moved from its locking position without showing that it has been tampered with.

5. A car door locking device comprising a base, a locking part slidably and rotatably mounted in said base so that it may be rotated and also moved longitudinally, a locking projection projecting laterally from said locking part, an engaging device connected with the body of the car adapted to be engaged by the locking projection by giving the locking part a longitudinal and rotating movement, a stop for preventing the locking part from being moved longitudinally when the locking projection is in its locking position, and means for preventing the locking part from being rotated while it is in its unlocked position.

6. A locking device for sliding car doors comprising a base, a locking part mounted therein so that it may be rotated and also

moved longitudinally when in a predetermined position, a locking projection projecting laterally from the locking part, an engaging part on the car body with which said locking projection is put into engagement by a rotating and longitudinal movement of the locking part, a second lateral projection on the outer side of the base and provided with a recess adapted to form a portion of a receiving space for a frangible seal, a seal breaking part connected with said lateral projection, means for holding a frangible seal so that a portion thereof projects over said latter projection whereby the movement of said locking part mutilates said seal.

7. A car door locking device comprising a base, a locking part slidably and rotatably mounted in said base so that it may be moved longitudinally and may be rotated, a laterally projecting locking projection on said locking part, an engaging device connected with the body of the car adapted to be engaged by the locking projection by giving the locking projection a longitudinal and rotating movement, a stop extending across said locking part, a shoulder on said locking part adapted to engage said stop when the locking part is in its locking position so as to prevent longitudinal movement of the locking part, said shoulder moved out of the way of said stop when the locking part is rotated so that the locking part may be moved longitudinally, said stop engaging the locking part after it has been moved longitudinally to its inoperative position so as to prevent the rotation of the locking part while in said unlocking position, but permit its longitudinal movement.

In testimony whereof, I affix my signature in the presence of two witnesses this 10th day of January, 1917.

FRED BERGWALL.
